ASHTRAY

Ernest W. Ekstrand, New Rochelle, N. Y., assignor to Ekstrand Mfg Co., Inc., New York, N. Y.

Application July 17, 1935, Serial No. 31,791

1 Claim. (Cl. 131—51)

My invention relates to ash trays for use by cigarette and cigar smokers.

The object of my invention is to provide a tray construction adapted to hold cigarettes or cigars in a practically vertical position in the act of extinguishing the lighted or burning ends thereof, formed to provide a plurality of small shallow chambers open at the top only, and arranged in a group in a manner to provide thin walls, the opposite sides of which serve as a wall for the adjacent chamber, said chambers being formed in a shape other than cylindrical so that the thickness of the walls will be substantially the same throughout their length.

15 A further object is to provide a construction having chambers or cells of such dimensions and form as will serve to act as snuffers for cigarettes placed therein.

A further object is to provide a tray of this character that may be easily moulded in a single piece and that will be ornamental in appearance.

Referring to the drawing which forms a part of this specification,

Fig. 1 is a plan view of a tray construction disclosing cells triangular in form, and also providing a dish-like receptacle for ashes etc.

Fig. 2 is a cross sectional view taken on line 2—2 of Figure 1.

Fig. 3 is a fragmental sectional view disclosing the form of one of the dividing walls of a cell, taken on line 3—3 of Figure 1.

I prefer to make the trays of glass or bakelite, but they may be made of any suitable material.

The tray 10 is preferably made with a flat bottom 11 so that the cells 12 will be of equal depth and the bottom of uniform thickness under the cells, so that when cast of glass the glass will not crack in cooling.

40 The tray may be made with a rim 14, the top edges of the cell walls 15 extending in a plane below the surface 14 and are preferably formed with narrow rounded top edges as illustrated at 16 in Figure 3.

In any event they are formed with narrow top

edges so that ashes will not lodge thereon but will fall into the cells.

The dotted lines forming the circle 18' indicate the diameter of a cigarette to illustrate the relative size of a cell in which it rests, the drawing 5 being made on a full size scale.

A lighted cigarette placed in a cell with its burning end in contact with the bottom thereof is soon extinguished by the carbon dioxide generated and held in the cell, thus excluding the 10 oxygen of the air required for combustion.

As clearly illustrated, a considerable number of cigarettes may be snuffed before it is necessary to empty the tray, and the tray is easily emptied since there are no overhanging parts to obstruct 15 the removal of the refuse therefrom.

Having thus described my invention I claim as new:

A tray of the character described formed to provide a circular bottom wall and an upstanding 20 marginal annular wall, a vertical partition wall extending across the bottom wall between portions of the annular wall substantially at the transverse median line of the tray, a segment-shaped block integral with the bottom and annular wall with the straight side of the segment-shaped block spaced from and parallel to the partition wall and defining an elongated recess, 25 a relatively thin zig-zag wall in the recess between the segment-shaped block and partition wall and integral with said block and wall, said zig-zag wall forming a plurality of cells triangular 30 in plan view with opposite sides of each section of the zig-zag wall forming a wall of adjacent cells, said cells having a depth greater than the 35 diameter of a cigarette, the circle circumscribed by each of the triangular contours having a diameter sufficiently greater than the diameter of a cigarette whereby an adjacent wall may support a cigarette at an acute angle relative to the vertical median line through a cell and said triangular cells being operative to reduce the amount of air admitted to the bottom thereof for positively extinguishing a cigarette.

ERNEST W. EKSTRAND.
